UNITED STATES PATENT OFFICE.

HENRY GEHRING, OF CLEVELAND, OHIO.

DESIGN FOR A FOUNTAIN FOR DISPENSING BEVERAGE.

Application filed February 4, 1925. Serial No. 12,264. Term of patent 3½ years.

To all whom it may concern:

Be it known that I, HENRY GEHRING, a citizen of the United States, residing at Cleveland, in the county of Cuyahoga and State of Ohio, have invented a new, original, and ornamental Design for Fountain for Dispensing Beverage, of which the following is a specification, reference being had to the accompanying drawing, forming part thereof.

The figure is a side elevation of a fountain for dispensing beverage showing my design.

I claim:

The ornamental design for a fountain for dispensing beverage, as shown.

HENRY GEHRING,
